UNITED STATES PATENT OFFICE.

CHARLES OSCAR MARX, OF BROOKLYN, NEW YORK, ASSIGNOR OF ONE-HALF TO
BERNARD SPITZADEN, OF BROOKLYN, NEW YORK.

DOOR-HANGER.

974,089.

Specification of Letters Patent. Patented Oct. 25, 1910.

Application filed June 25, 1909. Serial No. 504,335.

To all whom it may concern:

Be it known that I, CHARLES OSCAR MARX, a citizen of the United States, residing at Brooklyn, in the county of Kings and State of New York, have invented certain new and useful Improvements in Door-Hangers, of which the following is a specification.

My invention relates to improvements in a door hanger and it is specially adapted for use on elevator doors.

The object of the invention is to produce a durable and noiseless construction for the purpose mentioned, wherein friction between the track and roller is reduced to a minimum.

With these and other objects and advantages in view the invention comprises a novel construction and arrangement of parts, particularly described hereafter and pointed out in the claims appended hereto.

In the drawings annexed to and forming a part hereof—Figure 1 is a perspective view of the top of a door with the hanger and track in operative position. Fig. 2 is a transverse sectional view of one of the hangers and track; Fig. 3 an enlarged side elevation of the invention. Fig. 4 is a top plan view of the hanger; Fig. 5 is a modified form of track and Fig. 6 is a still further modification thereof.

Like numerals designate like parts throughout the views of the drawing.

The hanger is composed of a base plate 1, which is formed with parallel up-turned flanges 2 and 3, perforated as at 5 for permanent attachment to a hanger frame 7, by means of rivets or pins 6. While in this instance I have shown pins extending from flange to flange and up-set at each end, to securely fasten the hanger frame and base plate together and brace the same, it is to be understood that this connection may be made simply by riveting each flange to the depending branches of the hanger frame 7. The branches of the hanger-frame 7 are perforated at 8, said perforations registering with the perforations 5 in the flanges of the base plate 1. The base plate is elongated and at each end is provided with screw openings or perforations 9. It is secured to the top of the door 10 by means of screws 11, or other suitable fastening means where the door may be constructed of metal. The base plate and hanger frame are preferably formed of any suitable metal and the said

hanger frame is in the shape of a strap of suitable length bent U-shaped and inverted. At a suitable distance from the arch 12 thereof the hanger frame is braced by two pins 13 and 14 projecting from one side of the frame to the other with their ends up-set to securely brace the sides of the said frame, in conjunction with the pins 6. The said pins 13 and 14 are located above and out of contact with the metallic roller 15 and are so spaced apart that the said roller operates therebetween but below the same.

The roller is preferably spherical in shape with plane sides 16, contiguous to the depending sides or arms of the frame 7. It is journaled in position a suitable distance above the base by means of journal pins 18 and 19, to permit the track 17 to enter the frame thereunder. These journal pins have conical bearing points 20 and are threaded on the cylindrical body portion thereof as at 21. These pins are threaded into the said frame at opposite sides, which for the purpose of reinforcement, is provided with plates 22, securely riveted or otherwise fastened to the outside of the depending arms or portions of the frame. Instead of reinforcing plates the frames may be formed with integral enlargements at this point. The openings 23 in these plates, register and are threaded to receive the journal pins 18 and 19. To prevent these pins from moving after they are once positioned, a set screw 24 is employed; this set screw is threaded into an opening 25 in each of the plates 22, which said opening is formed at right angles to the position of the opening for the journal pins 18 and 19 and extends through the plate to the opening for the journal pin. This arrangement permits the set screws to impinge upon the said journal pins, and maintain them immovably in position. The conical bearing points of the pins 18 and 19 are journaled in conical depressions or bearings 26, arranged in the opposite plane sides of the roller and at the center thereof. The roller is preferably constructed of case-hardened metal and travels upon a track located beneath the same and between the depending sides of the frame which are spaced apart only sufficiently to permit the hanger frame to operate on the track without binding therein. The object is to align the centers of the roller and track parallel with the said depending sides. Of course it will be

understood that there are two or more hanger frames located upon the top of each door.

The track 17 is preferably constructed of 5 steel tubing rotatably mounted in brackets 26. These brackets are formed with projecting parts 27, having openings 28 in which the ends of the tubular track are rotatably seated. The base of each bracket is 10 provided with slotted openings upon opposite sides of the projection 27 through which fastening devices 29 connect the same adjustably with the door frame or inclosure of the elevator shaft.

15 In Fig. 5, is shown a modified form of track 17^a which is constructed of a solid circular bar of steel and in Fig. 6 there is shown a still further modification of track. The construction as here shown is a longitudinal segment of steel tubing arranged 20 with the circular part 17^b thereof uppermost and reinforced by an integral rib 17^c underneath and extending longitudinally of said segment. Both of the modified forms 25 of rotatable track, namely, 17^a and 17^b are intended to be used in conjunction with brackets similar to those employed in the preferred form of construction, and to this end, the modification shown in Fig. 6, has 30 its integral rib 17^c, restricted in height to the diameter of the segmental part of said modified form of track.

The advantages of the construction and arrangements of parts hereinbefore described 35 are as follows: There is a minimum of friction between the hanger frame and the track and also a minimum surface for friction between the roller and the track so that the door will travel upon the track with little noise and 40 friction and the hanger frames are not apt to bind and cause the door to lodge; also

the track may be rotated in its bearings from time to time to present an unworn surface to the roller. This will overcome the increase of friction caused by the wearing 45 of a flat surface upon the track. The construction shown in Fig. 6 is also adapted to be rotatable as described to prevent a flat surface being presented to the roller, although with this form of construction complete rotation of the track is not made. 50

Having thus fully described my invention what I claim as new and desire to secure by Letters Patent of the United States is:

1. The combination of a door-hanger-frame, a convex track, a convex roller rotatably mounted in said hanger-frame, and brackets having projecting members adapted for rotatably seating said track therein. 55

2. The combination with a door-hanger-frame, of a convex-roller journaled in said frame, and a convex track for said roller, rotatably seated in end supporting brackets, said hanger frame being constructed with depending sides spaced apart to aline the 60 centers of said roller and track parallel with said depending sides. 65

3. The combination with a door hanger frame, provided with parallel depending sides, and a convex track, of a roller rotatably mounted in said frame and constructed with a cylindrical tread adapted to travel on said track, the said depending sides of the hanger frame being spaced apart to aline the centers of the roller and track parallel with the said depending sides. 70 75

In testimony whereof I affix my signature in presence of two witnesses.

CHARLES OSCAR MARX.
